8 Claims. (Cl. 315—39.77)

(Granted under Title 35, U.S. Code (1952), sec. 266)

The invention described herein may be manufactured and used by or for the Government of the United States of America for governmental purposes without the payment of any royalties thereon or therefor.

This invention relates in general to magnetrons and in particular to a magnetron capable of generating electromagnetic wave energy having wavelengths of the order of 1 mm. and radiating such energy directly into space.

In the field of centimeter and millimeter electromagnetic wave energy generation and radiation it has become increasingly difficult to provide structures for generating electromagnetic wave energy having the shorter wavelengths due primarily to the fine machine work required in shaping the anodes of the magnetrons. With the high efficiency of the magnetron, and its ability to generate large amounts of microwave power, it is desirable to extend the use of this device to electromagnetic energy having shorter wavelengths thereby providing means to advance progress in this field. The present invention avoids the disadvantages of prior art devices and provides a magnetron whose anode can be fabricated with relative ease and which can be readily adapted to radiate directly into space.

Accordingly, it is an object of this invention to provide a magnetron capable of generating electromagnetic wave energy having wavelengths of the order of one millimeter.

It is another object of the present invention to provide a magnetron for millimeter wavelength energy generation whose anode can easily be fabricated.

It is a further object of this invention to provide a magnetron which can radiate directly into space.

It is a further object of the present invention to provide a magnetron for millimeter wavelength energy generation whose anode can easily be fabricated and which can radiate directly into space.

Other objects and advantages of this invention will become apparent upon a careful consideration of the following description when read in conjunction with the accompanying drawings in which like reference numerals designate like parts throughout the figures thereof and wherein:

Fig. 1 shows a schematic diagram of a first embodiment of the invention.

Fig. 2 is a schematic diagram of some of the components depicted in Fig. 1.

Fig. 3 is a schematic diagram of components depicted in Fig. 2.

Fig. 4 is a schematic diagram of the portion of the anode effecting radiation into space.

In accordance with the teachings of the present invention of self-radiating magnetron is provided which is capable of generating electromagnetic energy of the order of one millimeter in wavelength and radiating this energy into space directly from the magnetron anode. The anode of the embodiment for radiating such energy will consist primarily of molybdenum or tungsten sheeting formed into a cylinder with an array of apertures equally spaced around a substantial portion of the periphery of

2

the anode. Apertures are omitted in one position or in more than one alternate positions with the section having one aperture where three or more ordinarily would be effecting radiation into a space in selected direction.

Referring to Fig. 1, envelope 11 is an evacuated structure which surrounds anode 12 and has extending through it leads to a cathode heater and to the cathode, neither of which is shown in this figure. Etched through anode 12 are slots 13 which are uniform in shape and spaced 10 equally around the periphery of the anode with the exception of the positions indicated at 15 where slots are omitted. The heater and cathode leads enter the anode through insulator 16 which also serves as a support for the cathode and attachments thereto. The cathode heater is energized by A.-C. current from A.-C. power supply 19, although D.-C. current may be used, while an electric field between anode 12 and the cathode is established through power from D.-C. supply 18. A unidirectional magnetic field indicated at B with an arrow in the direction of the field is established by conventional means not shown in the drawings.

Fig. 2 shows in detail the interior of anode 12 in cross section. Cathode 21, which is coated with a suitable electron emissive material, is shown within anode 12 supported in position by leads 23 which serve the additional functions of supplying heating current to the cathode heater, not shown in this figure, and energizing the cathode from D.-C. power supply 18. "Hats" or collars 22 are hollowed metallic cups which have a fitting, not shown in this figure for purposes of simplification, extending from each closed end toward and enclosing the ends of cathode 21. Collars 22 are axially disposed within the anode such that facing edges 24 are beyond the extremities of a position on the cathode established by radially projecting any slot to the cathode. The collars serve to restrain electrons from moving axially thus insuring that the electrons interact with the R.-F. fields in the vicinity of the anode.

Fig. 3 depicts construction details of cathode 21 and its position relative to anode slots 13. Tubular fittings 25 of collars 22 at one end of cathode 21 hold the cathode in position and at both ends thereof serve to deter electrons from moving in directions not desired. An electric field E is established by energizing the anode and cathode from D.-C. power supply 18. Heater coil 27 produces thermionic emission from cathode 21 upon being energized by power supply 19.

Fig. 4 shows in details the portion of the magnetron effecting radiation into space. Anode 12 is shown in section along a plane perpendicular to the axis thereof and bisecting the slots 13. The stream of electrons indicated at A, having a pattern as shown which is explained hereinafter, approaches the anode in areas where electromagnetic wave energy indicated at 30 is opposite in direction to the stream of electrons while that indicated at 31 is similar in direction to the electron stream. Areas indicated at 33 and 34 are positions where slots have been omitted and where the radiation indicated at 35 occurs. It will be noted that the radiation at 35 extends a substantial distance from anode 12 due primarily to three successive fields having the same direction and complementing one another.

In operation, cathode 21 is heated by A.-C. power causing electrons to be emitted which are driven in a cycloidal motion by the combined magnetic field indicated at B and electric field indicated at E. As the moving electrons approach anode 12 they will be either retarded or accelerated according to the direction of waves 30 or 31 they encounter. Those electrons encountering an op-

posing R.-F. electric field will be retarded and because of their reduced velocity the Lorentz force

$$\text{tending to return them to the cathode will be reduced.}$$

$$(\rightarrow -ev \times \vec{B})$$

With properly adjusted electric and magnetic fields these electrons will make many such interactions forming the wave-like effect indicated at A in Fig. 4 and finally arriving at the anode after having given up a substantial amount of their energy to the R.-F. field. Those electrons encountering an accelerating R.-F. field will have their velocity increased thus increasing the Lorentz force tending to return them to the cathode. Because of the increased force the latter electrons will be driven into the cathode after one accelerating interaction and will abstract a negligible amount of power from the R.-F. field.

In the portion of the anode where apertures are successive the electron stream is driven, under the influence of a D.-C. electric field and an axial magnetic field, in such a manner that opposing fields are excited in the apertures. In such portion of the anode, fields at successive slots are 180° out of phase with each other (π -mode). Where π -mode exists the fields of successive apertures oppose one another thereby preventing radiation away from the anode in such portions thereof.

Where alternate apertures are omitted the remaining apertures are driven in phase thereby permitting radiation at one aperture to complement and amplify that at another.

The array of apertures is resonant at a frequency for which the apertures are a half wavelength long and presents a high coupling impedance to a stream of electrons passing close to the apertures. A primary feature of the present invention is that wavelengths of the order of one millimeter may emanate from a structure in which the necessary narrow apertures are made within close tolerances by processes such as etching as compared with the more difficult process of fabrication required to shape anodes of prior art devices in this particular field.

The stream of electrons is controlled so as to move within the anode across the array of slots 13 therein. The slots will be resonant, and thus present a high coupling impedance to the stream when passing close thereto, at a frequency for which the slots are a half wavelength long. The nominal anode voltage for beam-slot interaction is given by the formula

$$V_0 = 1.022 \times 10^6 \left[\frac{D}{\lambda(\Delta + 2n)} \right] \quad (1)$$

D =distance between successive slots in millimeters

λ =wavelength in millimeters

Δ =phase difference between successive slots in radians, divided by

n =an integer

The nominal magnetic field for beam-slot interaction is given by the formula

$$B_0 = \frac{4.284 \times 10^4}{N\lambda(\Delta + 2n) \left(1 - \frac{r_c^2}{r_a^2} \right)} \quad (2)$$

gauss where

r_c =cathode radius

r_a =anode radius

N =number of slot positions

Since successive electro-magnetic fields across successive slots are opposite in direction and therefore tend to cancel one another, self-radiation for a substantial distance is obtained by omitting one slot or more than one slot in alternate spaces around the anode. It may be shown that an array of slots of this nature will radiate in a

direction θ with respect to the plane of slots according to the equation

$$\frac{2D}{\lambda} \cos \theta = \Delta \quad (3)$$

and since $\cos \theta \leq 1$, no radiation will occur unless

$$D \geq \frac{\lambda \Delta}{2} \quad (4)$$

10 Assuming the electron beam will excite the conventional π -mode, for which $\Delta=1$, the structure can be prevented from radiating by making

$$D < \frac{\lambda}{2}$$

Modifying the structure over a small section by omitting alternate slots will cause a beam that has been bunched by the π -mode section to excite the $\Delta=0$ mode in the modified section. From Equation 3 it is seen that this section will 20 radiate in a direction normal to the structure. The degree of coupling can be controlled by the number of omitted slots.

With such a source of millimeter wavelength available, studies heretofore not possible can be made. Some of 25 these studies are experiments in the superconductivity of metals, diagnosis and measuring densities in fusion work and the determination of possible "windows" in the atmosphere, i.e. frequency bands where atmospheric attenuation is relatively low. Advances in the field of 30 communications can be considerable where the factors of flexibility, difficulty of detection, antenna size and antenna beam size are considered.

Many modifications and variations of the present invention are possible pursuant to the above teachings. It is 35 therefore to be understood that the practice of this invention is not limited by the specific examples in the foregoing description nor by the theoretical explanation of its operation that has been presented. As an example, the anode may be of other material than that disclosed 40 for the preferred embodiment. This invention is only to be limited by the scope of the appended claims.

What is claimed is:

1. A magnetron comprising an evacuated envelope containing an anode in the form of a hollow cylinder having a plurality of equal divisions which are equally spaced around said cylinder, a plurality of uniformly shaped apertures lesser in number than said plurality of divisions and having centers which are coplanar, each of said apertures positioned in the center of one of said plurality of divisions, said divisions without aperture being disposed at least one to each side of said divisions having apertures, means for generating a magnetic field extending axially through said cylinder, and means for developing a stream of electrons around the axis of said cylinder which interacts with said apertures such that said anode will resonate at a predetermined frequency.

2. A magnetron comprising an evacuated envelope containing an anode in the form of a hollow cylinder having a plurality of equal divisions which are equally spaced around said cylinder, a plurality of uniformly shaped apertures lesser in number than said plurality of divisions and whose centers are coplanar, each of said apertures positioned in the center of one of said plurality of divisions, said divisions without aperture being disposed at least one to each side of said divisions having apertures, and electron stream means including a source of electrons to excite said anode apertures at a predetermined frequency, said electron stream means including anode energizing means and a magnetic field to produce curvilinear motion of said electron stream and interaction of said stream with said apertures.

3. A magnetron comprising an evacuated envelope containing an anode in the form of a hollow cylinder having a plurality of equal divisions which are equally spaced around said cylinder, a plurality of uniformly

shaped apertures lesser in number than said plurality of divisions and whose centers are coplanar, each of said apertures positioned in the center of one of said plurality of divisions, said divisions without aperture being disposed at least one to each side of said divisions having apertures, means providing a source of electrons within the cylindrical space defined by said anode, and electric field producing means and magnetic field producing means for subjecting said electrons to the action of mutually perpendicular electric and magnetic fields such that a stream of electrons is produced which interacts with said apertures, said plurality of apertures shaped to resonate at a predetermined frequency, said disposition of said apertures in said divisions such that said predetermined frequency will be radiated unidirectionally along a line normal to said hollow cylinder.

4. A magnetron comprising an evacuated envelope containing an anode in the form of a hollow cylinder having a plurality of equal divisions which are equally spaced around said cylinder, a plurality of uniformly shaped apertures lesser in number than said plurality of divisions and having centers which are coplanar, each of said apertures occupying one of said plurality of divisions without aperture, said divisions without aperture being disposed at least one to each side of said divisions having apertures, electron source means including a cylindrical cathode axially positioned within said cylinder and extending a distance radially disposed from said apertures and substantially equal in length thereto, and means for developing a stream of electrons around the axis of said cylinder which interacts with said apertures such that said apertures will resonate at a predetermined frequency.

5. A magnetron comprising an evacuated envelope containing an anode in the form of a hollow cylinder having a plurality of equal divisions which are equally spaced around said cylinder, a plurality of uniformly shaped apertures lesser in number than said plurality of divisions and whose centers are coplanar, each of said apertures positioned in the center of one of said plurality of divisions, said divisions without aperture being disposed at least one to each side of said divisions having apertures, electron source means including a cylindrical cathode axially positioned within said cylinder and extending a distance radially disposed from said apertures and substantially equal in length thereto, a collar in the form of a metal hat positioned at each end of said cathode for restraining electrons from axial motion, and means for developing a stream of electrons around the axis of said cylinder which interacts with said apertures such that said apertures will resonate at a predetermined frequency.

6. A magnetron comprising an evacuated envelope containing an anode in the form of a hollow cylinder having a plurality of uniform apertures with the centers thereof coplanar about the circumference of said cylinder, said apertures having a slot configuration with the longitudinal axis of the slot substantially parallel to the axis of said cylinder, said circumference of said cylinder being divided into first and second sections, said first section having said apertures equispaced with a predetermined spacing therebetween, said second section having a plurality of apertures including a first aperture, a second aperture and a third aperture adjacent one another, said first aperture equidisposed between said second aperture and said third aperture at distances substantially

twice said predetermined spacing, said second aperture and said third aperture disposed said predetermined spacing from respective next adjacent apertures in said first section, means providing a source of electrons within the cylindrical space defined by said anode, and electric field producing means and magnetic field producing means for subjecting said electrons to the action of mutually perpendicular electric and magnetic fields such that a stream of electrons is produced which interacts with said apertures, said plurality of apertures shaped to resonate at a predetermined frequency, said spacing of said apertures in said second section such that said predetermined frequency will be radiated unidirectionally along a line normal to said hollow cylinder.

7. A magnetron comprising an evacuated envelope containing an anode in the form of a hollow cylinder having a plurality of uniform apertures with the centers thereof coplanar about the circumference of said cylinder, said apertures having a slot configuration with the longitudinal axis of the slot substantially parallel to the axis of said cylinder, said circumference of said cylinder being divided into first and second sections, said first section having said apertures equispaced with a predetermined spacing therebetween, said second section having a plurality of apertures including a first aperture, a second aperture and a third aperture adjacent one another, said first aperture equidisposed between said second aperture and said third aperture at distances substantially twice said predetermined spacing, said second aperture and said third aperture disposed said predetermined spacing from respective next adjacent apertures in said first section, electron source means including a cylindrical cathode axially positioned within said cylinder and extending a distance radially disposed from said apertures and substantially equal in length thereto, and means for developing a stream of electrons around the axis of said cylinder which interacts with said apertures such that said apertures will resonate at a predetermined frequency.

8. A magnetron comprising an evacuated envelope containing an anode in the form of a hollow cylinder having a plurality of uniform apertures with the centers thereof coplanar about the circumference of said cylinder, said apertures having a slot configuration with the longitudinal axis of the slot substantially parallel to the axis of said cylinder, said circumference of said cylinder being divided into first and second sections, said first section having said apertures equispaced with a predetermined spacing therebetween, said second section having a plurality of apertures including a first aperture, a second aperture and a third aperture adjacent one another, said first aperture equidisposed between said second aperture and said third aperture at distances substantially twice said predetermined spacing, said second aperture and said third aperture disposed said predetermined spacing from respective next adjacent apertures in said first section, and electron stream means including a source of electrons to excite said anode apertures at a predetermined frequency, said electron stream means including anode energizing means and a magnetic field to produce curvilinear motion of said electron stream and interaction of said stream with said apertures.
